CROSSING SLAB

Filed June 26, 1928

FIG. 1.

FIG. 2.

George E. Nagel,

BY

Geo. P. Kimmel

ATTORNEY.

UNITED STATES PATENT OFFICE

GEORGE E. NAGEL, OF COLUMBUS, OHIO

CROSSING SLAB

Application filed June 26, 1928. Serial No. 288,346.

This invention relates to railroad crossing slabs of concrete, and has for its object to provide, in a manner as hereinafter set forth, a slab of such class constructed in a manner to increase both the shearing and beam strength thereof.

A further object of the invention is to provide, in a manner as hereinafter set forth, a slab of the class referred to with new and improved truss elements for supporting, spacing and tying the upper and lower courses of the reinforcing bars of the slab in a thoroughly efficient and durable manner, and further by forming the truss elements where the reinforcing bars pass therethrough in a manner as to provide for uniform strength at such point.

Experience in the manufacture and use of concrete crossing slabs has proven that shearing stresses exerted by heavy motor truck traffic require a method of tying the upper and lower courses of the reinforcing bars of the slabs together to increase the life of the latter, and this requirement is accomplished by the truss elements, in accordance with this invention, and at the same time giving a truss effect which greatly increases both the shearing and beam strength of the slab.

Further objects of the invention are to provide in a concrete crossing slab spacing truss elements for the reinforcing bars thereof which are simple in construction and arrangement, strong, durable, thoroughly efficient in their use, and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a longitudinal sectional view

of a crossing slab in accordance with this invention.

Figure 2 is a section on line 2—2 Figure 1.

The slab comprises a body portion 1 of concrete, an upper course of reinforcing bars, 2, a lower course of reinforcing bars 3, and a series of spaced pairs of truss elements 4 and with each truss element formed of a pair of oppositely disposed truss members. The reinforcing bars are disposed lengthwise of the body portion 1 and the bars of the upper course are anchored together and the bars of the lower course are also anchored together or rather tied together. The bars of the upper course are tied to the bars of the lower course. The bars of each course are tied together and the bars of one course are tied to the bars of the other course by the spaced truss elements 4.

The oppositely disposed members which provide a truss element 4 are indicated at 5, 6 and as said members are of like construction, but one will be described, as the description of one will apply to the other.

Each truss member includes a pair of oppositely disposed, outwardly directed lateral end parts 7, 8 and a series of intermediate parts. The number of intermediate parts depend on the length of the truss members. The intermediate parts are alternately disposed with respect to the top and bottom of the member. As shown by way of example the truss member is formed with three intermediate parts 9, 10, and 11, and with the part 10 spaced from the parts 9 and 11.

The part 10 is oppositely disposed with respect to the parts 9, 11. Each end part has a squared outer side edge 12 and an inner end edge 13 inclining in opposite directions from the center thereof. Each end part furthermore has its outer end edge 14 inclining in opposite directions from its center thereby providing a point 15. The oppositely extending, inclined parts of the edge 14 are arranged in parallelism with respect to the oppositely extending, inclined parts of the edge 13.

Each intermediate part has its inner end edge 16 extending in opposite directions from the center thereof and its outer end edge 100

17 also extending in opposite directions at an inclination from the center thereof thereby providing a point 18. The inclined portions of the outer end edge 17 are disposed substantially parallel to the inclined portions of the inner edge 16. The end part 7 is connected to the intermediate part 9 by an inclined arm 20 of a width less than the length of the part 7 and also with respect to the length of the part 9. The intermediate part 10 is connected to the part 9 by an inclined arm 21 and the width of the latter is less than the length of the parts 9 or 10. The part 10 is connected to the part 11 by an inclined arm 22 and the width of the latter is less than the length of the part 10 or 11. The end part 8 is connected to the part 11 by an arm 23 which is disposed at an inclination and the width thereof is less than the length of the part 9 or 11.

20 The end parts and intermediate parts are provided centrally thereof with a circular opening 24 for the passage of a tie bar.

25 The end part 8 is constructed in the same manner as the end part 7, that is to say is provided with a squared outer side edge 24', an inner end edge 25 extending at opposite inclinations from the center thereof and an outer end edge 26 extending at opposite inclinations from the center thereof thereby providing a point 27. The inclined portions of the edge 26 are disposed substantially in parallelism with respect to the inclined portions of the edge 25.

30 35 The disposition of the inclined arms 20, 21, 22 and 23 with respect to the end and intermediate parts provides the truss member with alternately disposed, oppositely extending V-shaped parts or portions each having the closed terminal thereof provided by an intermediate part.

40 45 The length of the truss members preferably is slightly less than the width of the body portion 1 whereby the end parts thereof will be spaced adjacent the side edges of the body portion 1.

50 The end parts and intermediate parts are larger than the inclined connecting arms to provide for uniform strength at the portions of the member through which extend the reinforcing bars.

55 60 When a pair of truss members are arranged to provide the truss element, they abut against each other and are oppositely disposed. The truss members when in abutting position provide openings 28 for the passage of the concrete. The openings 28 are arranged between the end parts of the element. The truss element is also formed with a passage 29 at each end for the concrete. The truss element is furthermore so constructed as to provide V-shaped passages 30 for the concrete at top of the truss element and inverted V-shaped passages 31 at the bottom of

the truss element. The openings 28 and passages 29, 30 and 31 provide for the truss element to be rigidly anchored within the concrete body 1.

65 70 By reference to Figure 2 it will be noted that the upper course of reinforcing bars 2 is tied together by the truss element and also that the lower course of reinforcing bars 3 is also tied together by the truss element and further that the truss element ties the upper course of reinforcing bars 2 to the lower course of reinforcing bars 3. Further the truss element supports the bars of the two courses as well as maintains the same in spaced relation.

75 80 Certain of the bars of each course can be supported upon one corner thereof and the remainder upon a pair of corners thereof on the walls of the openings 24. See Figure 2.

85 An advantage possessed by the truss element is that the points at the bottom thereof can rest on the bottom of the mold while the concrete is being poured, accurately spacing the entire assembly with no ill-effect on the surface of the finished slab. By increasing 90 or decreasing the size of the reinforcing bars, the number of the truss elements and the length of these latter to strengthen the slab may be varied as conditions may require. Preferably the truss elements are stamped 95 from a length of sheet metal of the width desired resulting in no waste excepting where the openings 24 are provided. The small points of the truss elements coming to the surface of the slab are not objectionable, as 100 would be a flat piece of metal without the points that would tend to break the bond of the concrete. In some instances the points may be enclosed by the concrete due to the steel assembly slumping endwise, but preferably the points will be flush with the top and bottom surfaces of the body portion of the slab. However, it will be stated that the steel assembly does not slump to any material extent, the slump being negligible, and further in the majority of cases there is no slump whatsoevers.

105 110 The setting up of the slab with the truss elements constructed and arranged as referred to and illustrated provides a truss effect which greatly increases both the shearing and beam strength of the slab and further accurately spaces the entire assembly within the concrete body with no ill-effects whatsoever on the top and bottom surfaces of the slab, therefore it is thought the many advantages of a concrete slab, constructed in accordance with this invention, can be readily understood, and although the preferred embodiment of the invention is as illustrated and described, yet it is to be understood that changes in the details of construction can be had which fall within the scope of the invention as claimed.

What I claim is:

1. A truss member for concrete crossing slabs comprising a one-piece body having oppositely disposed, outwardly directed lateral end parts and oppositely and alternately disposed V portions, each having a terminal formed with an opening, and said body being further provided in each lateral end part with an opening aligning with an opening in a terminal. 5 70
2. In a truss element for concrete crossing slabs, a pair of oppositely disposed, opposed members each comprising a one-piece body having oppositely disposed, outwardly directed lateral end parts and oppositely and alternately disposed V portions, each of said V portions having a closed terminal formed with an opening to form a set of spaced openings at the top and at the bottom of the element, said body of each of said members being further formed in each lateral end part thereof with an opening, the openings at the ends of one member aligning with the upper set of openings and the openings at the ends of the other member aligning with the lower set of openings, said sets of openings providing for the passage of reinforcing bars whereby said element will support, space and tie said bars together. 15 20 25 85 90
3. A truss member for concrete crossing slabs comprising a one-piece body formed of oppositely and alternately disposed V portions each having a terminal formed with an opening, said body being further provided with outwardly directed lateral end parts each formed with an opening aligning with a terminal opening, and the apertured terminal of each V portion and the lateral end parts of said body being of a greater length than the width of the arms projecting therefrom forming the remaining part of a V portion. 30 35 40 45 50 55 60 65 75 80 85 90 95 100 105 110 115 120 125 130
4. A truss member for concrete crossing slabs comprising a one-piece body formed of oppositely and alternately disposed V portions each having a terminal formed with an opening, said body being further provided at each end with an opening aligning and with a point on its outer edge, the openings in said ends aligning with a terminal opening, and the apertured terminal of each V portion having a point formed centrally of its outer edge. 45 50 55 60 65
5. A truss member for concrete crossing slabs comprising a one-piece body formed of oppositely and alternately disposed V portions each having a terminal formed with an opening, said body being further provided at each end with an opening aligning and with a point on its outer edge, the openings in said ends aligning with a terminal opening, and the apertured terminal of each V portion having its outer edge provided with a point. 55 60 65 70 75 80 85 90 95 100 105 110 115 120 125 130
6. A truss member for concrete crossing slabs comprising a one-piece body formed of oppositely and alternately disposed V portions each having a terminal formed with an opening, said body being further provided at each end with an opening aligning and with a point on its outer edge, the openings in said ends aligning with a terminal opening, and the apertured terminal of each V portion having its outer edge inclining in opposite directions from the center toward the ends thereof to provide a point. 70 75 80 85 90 95 100 105 110 115 120 125 130
7. A crossing slab comprising a body portion, upstanding, oppositely disposed truss members arranged therein and each formed of oppositely and alternately disposed V portions merging into each other, each of said members having spaced openings at the upper and lower portions thereof, and reinforcing bars extending through the upper and lower openings and tied together by said members. 80 85 90 95 100 105 110 115 120 125 130
8. A crossing slab comprising a solid body portion, upstanding, oppositely disposed truss members arranged therein and each formed of oppositely and alternately disposed V portions merging into each other, each of said members having a set of openings in proximity to the top thereof and a set of openings in proximity to the bottom thereof, an upper set of reinforcing bars extending through said upper openings and tied together by said members, a lower set of reinforcing bars extending through said lower openings and tied together by said members, and said members further providing for tying the upper set of reinforcing bars to the lower set. 90 95 100 105 110 115 120 125 130
9. A crossing slab comprising a body portion, upstanding, oppositely disposed truss members arranged therein and each formed of oppositely and alternately disposed V portions merging into each other, each of said members having spaced openings at the upper and lower portions thereof, reinforcing bars extending through the upper and lower openings and tied together by said members, and each of said members at the top thereof provided with spaced points and at the bottom thereof provided with spaced points. 100 105 110 115 120 125 130
10. A crossing slab comprising a solid body portion, upstanding, oppositely disposed truss members arranged therein and each formed of oppositely and alternately disposed V portions merging into each other, each of said members having a set of openings in proximity to the top thereof and a set of openings in proximity to the bottom thereof, an upper set of reinforcing bars extending through said upper openings and tied together by said members, a lower set of reinforcing bars extending through said lower openings and tied together by said members, and said members further providing for tying the upper set of reinforcing bars to the lower set, each of said members at the top thereof provided with spaced points. 110 115 120 125 130

points and at the bottom thereof provided with spaced points.

11. A crossing slab comprising a concrete body portion, upstanding, oppositely disposed truss members arranged therein and each formed of oppositely and alternately disposed V portions merging into each other, each of said members having parts at the upper portions thereof provided with openings, said openings spaced from each other, each of said members having parts at the lower portions thereof provided with openings, the openings in the parts at the lower portions of the members being spaced from each other, reinforcing bars extending through said openings and tied together by said members, and the parts of said members provided with said openings being of a length greater than the width of the remaining parts of said members.

12. A crossing slab comprising a concrete body portion, upstanding, oppositely disposed truss members arranged therein and each formed of oppositely and alternately disposed V portions merging into each other, each of said members having parts at the upper portions thereof provided with openings, said openings spaced from each other, each of said members having parts at the lower portions thereof provided with openings, the openings in the parts at the lower portions of the members being spaced from each other, reinforcing bars extending through said openings and tied together by said members, the parts of said members provided with said openings being of a length greater than the width of the remaining parts of said members, and each of the parts of each of said members provided with an opening having its outer end edge formed with a point.

13. A crossing slab comprising a body portion, upstanding, oppositely disposed truss members arranged therein and each formed of oppositely and alternately disposed V portions merging into each other, each of said members having spaced openings at the upper and lower portions thereof, reinforcing bars extending through the upper and lower openings and tied together by said members, and the height of each of said members being substantially the same as the height of said body portion.

14. A cross slab comprising a solid body portion, upstanding, oppositely disposed truss members arranged therein and each formed of oppositely and alternately disposed V portions merging into each other, each of said members having a set of openings in proximity to the top thereof and a set of openings in proximity to the bottom thereof, an upper set of reinforcing bars extending through said upper openings and tied together by said members, a lower set of reinforcing bars extending through said

lower openings and tied together by said members, said members further providing for tying the upper set of reinforcing bars to the lower set, and the height of each of said members being substantially the same as the height of said body portion.

15. A crossing slab comprising a body portion, upstanding, oppositely disposed truss members arranged therein and each formed of oppositely and alternately disposed V portions merging into each other, each of said members having spaced openings at the upper and lower portions thereof, reinforcing bars extending through the upper and lower openings and tied together by said members, each of said members at the top thereof provided with spaced points and at the bottom thereof provided with spaced points, and the height of each of said members being substantially the same as the height of said body portion.

16. A crossing slab comprising a solid body portion, upstanding, oppositely disposed truss members arranged therein and each formed of oppositely and alternately disposed V portions merging into each other, each of said members having a set of openings in proximity to the top thereof and a set of openings in proximity to the bottom thereof, an upper set of reinforcing bars extending through said upper openings and tied together by said members, a lower set of reinforcing bars extending through said lower openings and tied together by said members, said members further providing for tying the upper set of reinforcing bars to the lower set, each of said members at the top thereof provided with spaced points, and at the bottom thereof provided with spaced points, and the height of each of said members being substantially the same as the height of said body portion.

17. A crossing slab comprising a concrete body, an upper set of spaced reinforcing bars embedded therein, a lower set of spaced reinforcing bars embedded therein, and upstanding, oppositely disposed truss members within said body, each of said truss members provided with spaced means in proximity to the top and bottom thereof for supporting, spacing and tying therewith certain of the bars of each of said sets.

18. A crossing slab comprising a concrete body, an upper set of spaced reinforcing bars embedded therein, a lower set of spaced reinforcing bars embedded therein, and upstanding, oppositely disposed truss members within said body, each of said truss members provided with means for supporting, spacing and tying therewith alternate bars of each of said sets, the bars of the upper set anchored by a truss member being alternately disposed with respect to the bars of the lower set anchored by said member.

19. A cross slab comprising a concrete

body, an upstanding truss member arranged therein and formed of opposed oppositely disposed V-portions merging into each other and an outwardly directed lateral end part 5 projecting of each of the outer V-portions, said member having parts at the upper portions thereof provided with openings spaced from each other, said member further having parts at the lower portions thereof provided 10 with a set of openings spaced from each other, said end parts provided with openings aligning with said sets of openings, and reinforcing bars extending through said upper and lower openings and tied together by said 15 member.

20. A cross slab comprising a concrete body, an upstanding truss member arranged therein and formed of opposed oppositely disposed V-portions merging into each other 20 and an outwardly directed lateral end part projecting of each of the outer V-portions, said member having parts at the upper portions thereof provided with openings spaced from each other, said member further having 25 parts at the lower portions thereof provided with a set of openings spaced from each other, said end parts provided with openings aligning with said sets of openings, and reinforcing bars extending through said 30 upper and lower openings and tied together by said member, said member having each of said parts provided with a point on its outer edge.

In testimony whereof, I affix my signature
35 hereto.

GEORGE E. NAGEL.
